CUTLERY HANDLE OR THE LIKE

Lowell W. Barrett, Golden, Colo., assignor to L. W. Barrett Company, Inc., Denver, Colo., a corporation of Iowa

Filed May 3, 1965, Ser. No. 85,070

Term of patent 14 years

(Cl. D44—29)

A serving spoon is shown by broken lines in FIGS. 1 and 2 for illustrative purposes only.

I claim:

The ornamental design for a cutlery handle or the like, as shown and described.
